SLIPPER OR SIMILAR ARTICLE

John A. Lacek, Dolgeville, N. Y., assignor to Daniel Green Company, Dolgeville, N. Y.

Application September 29, 1949, Serial No. 5,208

Term of patent 7 years

(Cl. D7—7)

To all whom it may concern:

Be it known that I, John A. Lacek, a citizen of the United States, residing at Dolgeville, in the county of Herkimer and State of New York, have invented a new, original, and ornamental Design for a Slipper or Similar Article, of which the following is a specification, reference being had to the accompanying drawing, forming part thereof.

In the drawing

Fig. 1 is a top plan view of a slipper, showing my new design;

Fig. 2 is a side view thereof; and

Fig. 3 is a bottom plan view thereof.

The essential features of the present design comprise the shape of the upper, the rear end of which extends upwardly and forwardly from the shank portion of the sole, exposing the upper surface of the bottom of the shoe rearwardly of the shank; and the lacing at the peripheral edge of the shoe bottom completely therearound, all as illustrated on the drawing.

I claim:

The ornamental design for a slipper or similar article, substantially as shown and described.

JOHN A. LACEK.
